PAPER PADDING PRESS

Charles S. Mallory and Henry C. Mallory, Grand Rapids, and Charles W. Marble and Charles M. Mumford, Detroit, Mich.; said Marble and said Mumford assignors to Charles S. Mallory and Henry C. Mallory

Application February 28, 1938, Serial No. 193,146

4 Claims. (Cl. 100—8)

This invention relates to paper padding presses or devices which assemble pads of paper preparatory to applying the binding adhesive thereto.

The principal object of the invention is to produce a simple press structure which is easily manipulated and possesses the requisite pressing medium with positioning and evening means for the piled sheets of paper.

A further object is to produce a light-weight yet rigid structure which may be shipped in knocked-down form and readily assembled at the place of use.

With these and other objects in view the invention consists in the structure and combinations and arrangements of parts hereinafter described and pointed out with particularity in the appended claims.

In the accompanying drawings illustrating a practical adaptation of the invention,

20 Figure 1 is a front elevation of the press;

Figure 2 is a top plan view;

Figure 3 is an end elevation;

Figure 4 is a fragmentary vertical section, on an enlarged scale, taken on or about the line 4—4 of Figure 1;

Figure 5 is a horizontal section on the line 5—5 of Figure 4; and

Figure 6 is a horizontal section on the line 6—6 of Figure 4.

30 Referring now to the drawings, the numeral 10 designates the base plate or board of the press which may be conveniently made of wood, preferably of the character known as "ply-wood." Obviously, however, it may be made of metal or

35 any other suitable material.

As shown, the base plate or board 10 is chamfered on its upper face along its opposite end portions, as at 11. Extending across one longitudinal side portion of the base 10 is a rectangular frame or yoke 12 of substantially inverted U-shape and of channelled cross section. This frame may be made of a single metal section and bent into the form shown, or, obviously, it may be formed of separate members and welded or otherwise secured together in any approved manner. At the opposite lower ends of the vertical leg portions of said frame or yoke 12 bolts 13 are attached or formed integrally therewith; preferably by welding, as shown more clearly at 14 in Figure 5. These bolts 13 are inserted in openings provided therefor in the base 10, which openings are countersunk at the under side of the base for the reception of nuts 15.

Extending horizontally near the intermediate 55 upper portion 16 of the yoke or frame 12 is a

cross member 17 which is welded or otherwise secured at its opposite ends to the adjacent leg portions of the frame, this cross member preferably being an inverted channel.

Depending vertically from the upper cross member 16, near the vertical legs of the frame 12, is a pair of tubes 18, while opposed to said tubes in axial alignment therewith is a pair of tubes 19 extending upwardly from the lower cross member 17, each of said tubes being rigidly secured to the respective cross member, preferably by welding. The aligned tubes 18 and 19 have smooth bores of the same diameter and extending therethrough are elongated screw elements 20 with free longitudinal movement therein, said screw elements being held against rotation during their longitudinal movement by being provided with longitudinal grooves 21 (see Figure 6) to receive splines or key members 22 which are fixed on the tubular members 18 or 20 15 19. For practical purposes, it is only necessary to provide the spline or key 22 on one of the opposed sleeves 18 or 19, and as shown this member is provided only on the lower sleeve 19.

Interposed between the respective upper and 25 lower sleeves 18 and 19 are hand wheels 23, the hub portions 24 of which have screw threaded bores to fit the screws 20, and as said hub portions 24 abut the adjacent ends of said sleeves 18 and 19 the hand wheels, of course, are held 30

against endwise movement during rotation. Consequently, when said wheels are rotated the screw elements 22 are caused to move endwise, either upwardly or downwardly, according to the 35 direction of rotation of the hand wheels, and due to the threaded engagement of the hub portions

24 with said screw elements 20. Any suitable anti-friction bearings may be provided between the abutting ends of the tubes 18, 19, and the hub portions 24 of the hand wheels, but, as 40 shown, a ball bearing 25 of any conventional type is interposed between the lower end of the hub 24 and the end of the lower sleeve 19, while between the upper sleeve 18 and upper end of the hub 24 a washer 26, of bronze or other suitable 45 anti-friction metal, is provided, as shown in Figure 4. However, as just previously noted, any other suitable provision may be made for the purpose of end thrust bearings between the hub 24 and sleeves 18 and 19.

50 At the lower ends of the screw elements 20 are foot elements 27, preferably elongated and of channelled section. These elements 27 may be attached to the lower ends of the screw elements 20 in any desirable manner, either rigidly or with 55

- limited relative movement therebetween. Preferably, they are rigidly secured, and the outer end of each foot element is extended into the adjacent channelled leg portion of the frame or 5 yoke 12 with freedom to move vertically therein whereby to be guided in operation and held against rotative movement about the axis of the companion screw element 20. As shown, the attachment of the foot element 27 to the screw 10 element 20 is effected by welding a triangular upstanding flange or lug 28 centrally upon the upper side of the web of the foot element and slotting the end portion of the screw element as at 29 (see Figure 4) to receive said flange or lug 15 28 and welding the parts together, as indicated at 30. Welded or otherwise secured to the under side of each of the foot elements 27 is a presser plate 31 of lesser length but of greater width than the foot element.
- 20 The yoke or frame 12 is braced by end plates 32 which are flanged at both front and rear vertical margins, as at 33 and 34, and also at their lower margins as at 35, in order to give rigidity to the plate and provide means for its attachment 25 to the frame or yoke 12 and also to the base 10, as will now be described.
- The vertical flanges 33 of the plates 32 are provided with a longitudinal series of apertures through which attaching screws 36 are inserted 30 into aligned screw threaded apertures provided therefor in the abutting flange portions of the leg members of the yoke or frame 12. A correspondingly apertured reinforcing bar 37 is preferably provided on the outside of the flange 33, 35 which not only affords a stable securing means for the flange but adds to the rigidity of the leg portions of the frame or yoke 12. The bottom flanges 35 of said plates 32 are provided with a series of apertures to receive attaching screws 38 40 which are inserted through openings provided therefor in the base 10, which openings are countersunk at the under side of the base to receive the securing nuts 39.
- The structure is further braced by the provision 45 of triangular gusset plates 40 which are flanged along one right angular marginal portion thereof, as at 41, which overhangs the upper marginal portion of the plate 32 and is secured to the plate by screws or bolts 42, and said plates 50 40 are detachably secured along their other right angular marginal portions to the lower horizontal frame member 17 by screws or bolts 43. In this connection, also, it is preferable to bolt the meeting end portions of the two gusset plates together, 55 by the same bolt or screw 44 which attaches them to said cross member 17 of the frame (see Figure 1). It is preferable to further reinforce the yoke or frame 12 by welding or otherwise securing a truss member 45 on top of the upper cross member 16 of the frame 12 and providing a strut 46 between the raised middle portion of the truss 45 and the cross member 16. This truss member 45 is provided with openings 47 for the free passage 60 of the upper end portions of the screw elements 20, and, obviously, said cross members 16 and 17 of the frame or yoke 12 are likewise provided with suitable openings aligned with the sleeve members 18 and 19 for the passage of said screw elements 20.
- 70 From the foregoing it is noted that a knocked-down structure is produced which is comparatively light in weight yet possesses the inherent rigidity requisite for a device of this character, and the general arrangement of the device is 75 such that the paper sheets may be conveniently

piled and evened for the application of the presser plate 31 thereto. An evener plate or what may be termed a "jogging board" 48 is provided for the device. As shown, this plate is provided at its opposite vertical edges with flanges 49 which are directed inwardly in overlapping relation to the vertical leg portions of the frame or yoke 12, said flanges being provided with inclined slots 50 to hook over shouldered studs or buttons 51 provided therefor on the vertical frame members, 10 whereby said evener plate or jogging board is readily placed upon and removed from the frame. To give the desired rigidity to the plate 48 its lower marginal portion is flanged outwardly, as at 52, which portion also serves as a convenient 15 grasping means for placing and removing the plate, while at the upper portion the plate is flanged inwardly, as at 53, to abut the outer flange of the cross member 17.

In the use of the device, plate 48 is placed on 20 the frame or yoke 12 and the piled sheets, indicated at 54 under the left presser plate 31 or under the other plate, or both plates, as may be the case, are pressed edgewise against the plate 48, and after the presser plate is brought to bear 25 upon the piled sheets through the instrumentality of the cooperating hand wheel 23 and screw elements 20, said plate 48 is removed and the exposed edge portion of the pressed pad is ready for the application of the binding adhesive. 30

Obviously, the structure may be modified in many respects within the spirit and scope of the invention as defined by the appended claims. The invention, therefore, is not limited to the specific construction and arrangement shown in 35 the accompanying drawings.

What is claimed is:

1. A paper padding press comprising a base plate, an inverted substantially U-shaped yoke frame detachably secured at its lower ends to said base plate, said yoke frame having a trussed horizontal top portion, and a lower horizontal cross member, opposed end plates having flanged lower marginal portions detachably secured to said base plate and flanged vertical marginal portions adjacent the leg members of said yoke frame, elongated reinforcing bars located on the outer faces of said flanged vertical portions of the end plates, said bars, plate flanges and adjacent yoke frame portions being provided with registered apertures, 40 securing bolts in said apertures, gusset plates detachably secured along their right angular outer marginal portions to said end plates and also to said lower cross member of the yoke frame, and pressing means carried by said yoke frame in 45 50 55 opposed cooperative relation to said base plate.

2. A knock-down paper padding press structure comprising a base plate, an upstanding inverted substantially U-shape frame having bolt extensions at its opposite lower ends, said base 60 plate having vertical openings therein for the reception of the bolt extensions of said yoke frame, securing nuts on said bolt extensions, the horizontal top portion of said yoke frame being trussed longitudinally said frame having a horizontal cross member below said top member, aligned vertical sleeve members mounted in 65 opposed spaced relation to each other on said top and lower frame members, a hand wheel having a hub portion interposed between said sleeve members, an elongated vertical screw element extending through said sleeve members and free of threaded engagement therewith but having a threaded engagement with the hub portion of said hand wheel, said screw element having a 70 75 80 85 90 95

- longitudinal slot and spline engagement with a sleeve member whereby, upon rotation of the hand wheel, longitudinal movement is imparted to the screw element, a foot member attached 5 to the lower end of said screw member, a presser plate located on the under side of said foot element in opposed relation to the base plate, opposite end plates having their lower marginal portions flanged, means for detachably securing 10 said flanged portions of the end plates to said base plate, the adjacent vertical marginal portions of said end plates being detachably secured to the vertical leg portions of the yoke frame, and a pair of triangular gusset plates having one 15 of their right angular outer marginal portions flanged and detachably secured to the top marginal portions of said end plates, the other right angular margin of each of said gusset plates being detachably secured to the lower cross member 20 of said yoke frame and the meeting corner portions of said gusset plates being overlapped and detachably secured to the middle portion of said lower cross member of the yoke frame.
3. A paper padding press comprising a base 25 plate, an upstanding inverted substantially U-shape yoke frame of general rectangular form and constructed of a metal element of channelled cross section, the horizontal intermediate top portion of the frame being longitudinally trussed 30 on its upper side, a lower cross member of channelled section attached at its opposite ends to the vertical leg members of the frame below the top cross member, means for detachably securing the ends of said yoke frame to the base plate, oppo-
- site end plates detachably secured at their lower marginal portions to the base plate and at their adjacent vertical marginal portions to the leg members of said yoke frame, gusset plates detachably connected to the upper marginal portions 5 of said end plates and to said lower cross member of the yoke frame, and a plurality of pressing units, each comprising a vertically movable power screw, a horizontal foot element secured on the lower end of the power screw, a 10 presser plate located on said foot element in opposed cooperative relation to said base plate, and a hand wheel for actuating said power screw.
4. A paper padding press comprising a rectangular base plate, an upstanding generally rectangular inverted substantially U-shape yoke frame mounted adjacent one side of said base plate, said yoke frame carrying a pressing medium 15 in opposed relation to the base plate, end plates rigidly secured at their lower marginal portions to the opposite right angular marginal portions of the base plate and at their vertical margins to the adjacent leg portions of the yoke frame, stud members projecting outwardly from 20 said leg portions of the yoke frame, and an evener plate having inturned flanges at its vertical margins to overlap said leg portions of the yoke frame and having notches for releasable interlocking engagement with the stud members on said leg 25 portions of the yoke frame.
